OIL BURNER

Richard M. Runge and Ernest B. Pascucci,
Meriden, Conn., assignors to The Miller Com-
pany, Meriden, Conn., a corporation of Con-
necticut

Application October 31, 1938, Serial No. 237,826

28 Claims. (Cl. 126—45)

The present invention relates to oil burners, and is more particularly directed toward oil burners of the wick type employing forced draft.

In oil burners of the type contemplated the draft is produced by an electric motor which operates a blower forcing the air through the burner or burners all the time that the motor is in operation. The forced draft passes up by the wick and this makes it possible to dispense with a chimney so that the burner may be close to the grate which supports the utensil to be heated, or may be close to the bottom of an oven.

According to the present invention each burner is provided with a snuffer which can be either held a sufficient distance above the wick so that a flame may be propagated, or which may be lowered to a position to extinguish the flame. Suitable mechanism is provided whereby the snuffer is releasable so as to drop to cover the top of the wick and cut off the air supply from the wick whereby the flame is extinguished. These releases are interconnected with the motor and air blower in such a way that upon failure of motor operation the releases disable the snuffer holding means so that the snuffer drops. This affords a safety factor which insures that there will be no possibility of the burner continuing to burn after the blower has ceased operation, as, for example, upon power failure.

Other and further objects of the invention will appear as the description proceeds.

The accompanying drawings show, for purposes of illustrating the present invention, several embodiments in which the invention may take form, it being understood that the drawings are illustrative of the invention rather than limiting the same.

In these drawings:

Figure 1 is a front elevational view of a flat top oil stove illustrating burners under the top of the stove and under the oven;

Figure 2 is a side elevational view of the stove of Figure 1;

Figure 3 is a perspective view illustrating a battery of four burners operated from a single motor and blower and having manual snuffer lifters and automatically controlled snuffer releases, the snuffers being shown in the upper or burning position;

Figure 4 is a vertical sectional view taken on the line 4—4 of Figures 3 and 6 illustrating two burners, the one at the left being in the burning position, the one at the right with the parts in position for lighting the wick with a match;

Figure 5 is a sectional view taken on the line 5—5 of Figure 4;

Figure 6 is an inverted plan view taken on the line 6—6 of Figure 4, parts being in elevation;

Figure 7 is a view similar to Figure 4, but showing the burner in the stop or off position with the snuffer lowered;

Figure 8 is a sectional view taken on the line 8—8 of Figure 7, the dot-and-dash line position of parts indicating the positions assumed preparatory to lighting the burner with a match;

Figure 8A is a fragmentary elevational view at an enlarged scale showing a detail;

Figure 9 is a longitudinal sectional view through a modified form of construction, the parts being shown in full lines in the burning position, the dotted line indicating the position assumed during lighting with a match and the dot-and-dash line indicating the manual release of the snuffer;

Figure 10 is a fragmentary view taken on the line 10—10 of Figure 9;

Figure 11 is a fragmentary longitudinal sectional view through a modified form of construction in which the snuffer is lifted by the government on the motor;

Figure 12 is a fragmentary sectional view on the line 12—12 of Figure 11;

Figure 13 is a top plan view of a battery of four burners arranged radially with respect to a central blower and air-chest, the full lines indicating position of parts when the stove is not operating, the dot-and-dash lines indicating parts in burning position;

Figure 14 is a vertical sectional view taken on the broken line 14—14 of Figure 13, the parts being in the burning position;

Figure 15 is a fragmentary sectional view taken on the line 15—15 of Figure 13;

Figure 16 is a fragmentary enlarged plan view taken in the direction of the arrow 16 of Figure 15;

Figure 17 is a vertical sectional view through a single burner unit with the motor mounted underneath the burner, the parts being in the burning position; and

Figure 18 is a perspective view of a space heater employing the burners shown herein.

Figures 1 and 2 illustrate a flat top stove of typical dimensions and appearance and might be a chassis designed to use the conventional burners of a gas stove or the heating units of an electric stove. It is here illustrated, however, as housing the burners for a forced draft oil stove. These burners may be carried directly below the

oven 20a. The upper burners are diagrammatically illustrated at 21 and the oven burners at 22. It will be noted that these burners with associated forced draft mechanism (illustrated in dotted lines) form a very shallow structure. In fact it occupies substantially the same space as the burners of a gas stove so that the same chassis may be used for the oil stove, and at the same time have the smooth top and the desirable storage cabinets which go in gas and electric stoves. All the controls are brought out to the front of the stove and the motor for supplying the draft and fuel tank are placed behind the stove.

In the arrangement shown in Figures 3 to 8, inclusive, there are four complete burner units connected to a single air-chest and provided with air by a single motor operated blower. The motor for operating the blower is indicated at 30, Figure 4. It is carried in a housing 31 apertured at the outer end, as shown at 32, to admit air and having an inner aperture 33 to permit air to be driven into the air-chest by a multiple bladed fan indicated at 34, this fan being driven by a shaft 35. The fan spider has a cone bearing surface indicated at 36, and the shaft carries a conical member 37 pressed toward the fan body by springs 38 carried on pins 39. Balls 40 are interposed between these two conical surfaces and when the motor is idle the parts are in the position shown in Figure 7, when the motor is running at speed these parts just described are in the positions shown in Figures 4 and 6. The fan or blower 34 is received in a box 41 which is connected with two forwardly extending conduits or air-chests 42. The openings between the box 41 and these conduits or air-chests are covered with a screen indicated at 43, which serves to bring about a more even flow of air throughout the entire cross sectional area of each of the air-chests 42.

Each of these air-chests 42 supports two burner units which may be identical. The top or cover 44 of the air-chest is provided with large openings 45 having aligning flanges 46 extending upwardly to fit the inside of a double walled wick tube 47 carrying a cylindrical wick W. Outside this wick tube the cover plate 44 is provided with a number of perforations 48 shown more clearly in Figure 6. These are adapted to pass air up into an outer air tube 49 concentric with the wick tube.

The wick tube is provided with a perforated diaphragm 50 which has a guide tube 50' to support an axially disposed rod 51. This rod extends up through a flame spreader 52 and carries an inverted cup-shaped snuffer 53 larger in diameter than the flame spreader and slightly larger than the upper outer wall of the wick tube. Between the diaphragm 50 and flame spreader 52 the wick tube carries an air distributor indicated at 54.

In the particular constructions shown herein, except Figure 17, the flame spreader and air distributor are separable. They may, however, be unitary somewhat as shown in Wilcox Patent 1,717,484. The separable form of flame spreader and air distributor admits of the lifting of the flame spreader 52 by the shoulder 55 on the rod 51, as will be apparent by comparing the position of these parts in the two burners of Figure 4. The purpose of lifting the flame spreader and snuffer to the higher elevation is to provide more room for the insertion of a match to the top of the wick.

75 The outer air tube 49 is drawn in, as indicated

in the drawings, so as to be brought close to the wick tube. It carries a constricted collar 56 whose upper edge is close to the top of the wick tube. This constricted collar is provided with a row of perforations 57 which is spaced above a shoulder 58 and this shoulder supports a fire collar 59 of suitable shape to divert the flame up toward the grate.

The wick tube is provided with the usual wick lifting mechanism including the gears indicated at 60 and shaft indicated at 61. Each of these shafts extends out through the respective outer air tube 49 and is connected by a suitable universal coupling 62 to an operating shaft 63 which extends out through the front of the stove where it is provided with an operating knob illustrated at 64, Figures 1 and 2. These control knobs make it possible to conveniently raise and lower the wicks to adjust the flame, or turn it out when burner operation is no longer desired.

The oil supply tubes are indicated at 65. They extend through couplings 66 in the outer air tubes 49 and into the usual couplings 67 carried by the wick tubes.

When the motor is not in operation the speed responsive mechanism is in the position shown in Figure 7, the parts to be acted on thereby are pushed to the rear of the stove. When the motor is in operation these parts are pushed toward the front. The cone 37 of the speed responsive mechanism has a ball 68, which bears on a spring 70 which in turn presses against a horizontal rod or cross bar 71. This cross bar is connected to a plunger 72 by a screw 72', and carries adjusting screws 72a and 72b bearing in the ends of plungers 73 and 74, which extend through the air-chests 42. The plungers 72 and 73 are urged to the rear by springs indicated at 75, while the plunger 74 (disposed between the air-chests) is urged to the rear by springs indicated at 76.

The plungers 72 and 73 extend under the two burners mounted on the respective air-chests. They are supported by downwardly bent apertured lugs 77 carried by the air-chest cover plate 44, and each rod carries a pin 78 (see Figure 8A) adapted to shift a latch 79 (pivoted to the guide tube 50') from the position shown in Figure 4 to the position shown in Figure 7 when the motor stops or the speed is materially reduced. The latch is moved to the right, as shown in Figure 4, by a spring 80 abutting a washer 80a held in place by a pin 80b. The latch is adapted to cooperate with a shoulder 81 placed near the lower end of the vertically reciprocable carrying rod 51. The lower end of this rod is reduced as indicated at 82.

The snuffer rods 51 are adapted to be manually lifted by knobs 83 extending out through the front of the stove. These knobs are connected to shafts 84 which extend through the air-chests 42 and are slidably carried under the cover member 44 by apertured lugs 85. Each of the rods 84 carries two lever arms 86 and 87. When the stove is in normal operation or when it is idle, the shafts 84 are in the angular position indicated in Figure 8, and the lever arms 86 and 87 are in the position shown in full lines in Figure 8. The shafts 84 can be moved axially in their bearings from a mid-position, as shown at the bottom of Figure 6, to the right, as shown by the shaft 84 at the top of Figure 6, or to the left a similar amount. This makes it possible to select which snuffer will be 75

lifted. The lower end 82 of each of the snuffer rods is above a lifter lever 88 pivoted on lugs 89 and having an extension 90 which is disposed below the lifter levers 86 or 87. When the rod 84 is in the longitudinal position shown at the bottom of Figure 6 and is turned from the full line position of Figure 8 to the dotted line position of Figure 8, both snuffer lifter levers 88 will be swung to the dot-and-dash line position of Figure 8. When the upper rod 84 of Figure 6 is in the longitudinal position indicated in that figure and a similar turning movement is made only the upper right hand lever 88 of Figure 6 will be affected, and, when the upper shaft 84 of Figure 6 is pushed all the way to the left, the arm 87 will be moved away from the corresponding snuffer lifter lever and the arm 86 only will engage its corresponding snuffer lifting lever. In this way it is possible to select which one of the snuffers will be lifted. The extent of lifting is shown in the dot-and-dash line position of Figure 8 and at the right hand burner of Figure 4, wherein it will be seen that the snuffer 53 and the flame spreader 52 have been lifted to an elevation above the normal burning position. This facilitates lighting the burner with a match. To temporarily reduce the air pressure and lessen the tendency to blow out the match, a trap 91 may be opened by the lifter lever 88.

It is, however, possible to light the burner with a match without having the snuffer at a higher elevation than that shown at the left of Figure 4, and, of course, where ignition other than by match is employed there is no occasion for lifting the flame spreader further away from the wick or for lifting the snuffer above the normal burning position, or for the trap.

When the parts are in the position shown in the dot-and-dash lines in Figure 8, the lever 86 is turned far enough to hold the snuffer in the elevated position, so that one need not maintain a grip on the control knob. As soon as the knob, however, is turned slightly to lower the snuffer, the snuffer drops down far enough to bring the shoulder 81 on the rod 51 against the latch assuming that the latch has been urged to the right by the speed responsive mechanism above described.

It will thus be seen that one can light any one or all of the burners or can extinguish the flame by turning down the wick and then relight the burner, and that the entire stove can be put out of operation by switching off the current to the motor by a convenient switch, such as indicated at 91.

In the operation of the stove both air chests are maintained at a definite and uniform pressure above the atmosphere by the blower, and should one or more burners be turned off there will be an air leakage around the burners that are turned off so that it will not materially interfere with the operation of the burners that are still burning. This air is blown up through the openings inside and outside the wick tube in a proportion which can be quite definitely controlled by selecting the proper size for the apertures through which the air enters as well as the size of the passages through which the air escapes upwardly in passing through the air distributor, collar and about the wick. An extremely hot flame is produced by the combustion of the fuel on the wick and the outer fire collar diverts this flame upwardly so that it can play directly on the oven or dish to be heated, the dish being supported by a grate 20 as usual. The snuffer 53 being larger

than the wick and covering the wick, the flame spreader and air distributor, it is obvious that the wick is very well protected against any foreign material dropping on to it.

In the form shown in Figures 9 and 10 most of the parts are the same as those shown in Figures 1 to 8, inclusive, and these common parts will not be again described, similar reference characters, however, being applied to them. Here shoulder 81 of the snuffer lifting rod 51 is engaged by a latching lever 100 pivoted at 101 to a plunger 102 and under the influence of spring 103. The plunger 102 is urged to the right by a spring 102' and is pushed to the left by the speed responsive mechanism, as above described. The snuffer lifting operation is effected by an arm 104 carried on a shaft 105 and movable as indicated in Figure 9. The snuffer can be tripped manually by an arm 106 carried by the shaft 105. This form of construction is more suitable for a plurality of burners in line with the fan axis, as it eliminates considerable of the mechanism shown in the four burner arrangement of Figure 3.

In the arrangement in Figures 11 and 12, the speed responsive mechanism operates on a spring 110 which in turn pushes a shaft 111 to the left. This shaft is provided with a cotter pin 112 engageable with a lifting lever 113 pivoted at 114 and acting to lift the snuffer rod 51 from the dot-and-dash line position to the full line position and to hold it there so long as the motor and blower are in operation. Snuffer lifting for lighting with a match is effected by a lever indicated at 115. With this form of construction all manual operation of the snuffer may be eliminated where one desires to effect the lighting without lifting the snuffer to the extra height, snuffer lifting and lowering being effected solely by the functioning of the blower and motor.

In the form of construction shown in Figures 13 to 16, inclusive, the motor for operating the blower is indicated at 120 and the blower at 121. The blower carries weighted members 122 adapted to lift a shaft 123 up and down according to the speed of the blower. The blower 121 is mounted in a housing 123' which has four outlets 124 leading to four burner assemblies, all of which are practically alike. The air passing from the central blower chamber to the air chest below each burner passes through screens indicated at 125 to diffuse it.

Each of the burner units has a wick, wick tube, air distributor, flame spreader, snuffer, fire collar and constricted collar, as shown in Figures 1 to 8, and the same reference characters are employed. The constricted collar 56 is supported on an outer air tube 126 detachably carried on the top of a cup-shaped air chest forming member 127. The outer air tube 126 carries bridging members 128 which support the wick tube. The cup-shaped member 127 supports a bridging strap 129 apertured to receive the snuffer rod guide tube 50' and also carries a pivoted latch 130 adapted to cooperate with the shoulder 81 of the snuffer guide rod, as will be more clear from Figures 15 and 16.

The latch 130 has a lost motion pin-and-slot connection 131 with a link 132 and a spring 133 interconnects the latch and link so as to hold the latch against the snuffer guide rod when the parts are in the position shown in Figure 16. The rods 132 are connected with an oscillatory plate 133 so as to be shifted when the plate is turned on its axis either by the handle 134 or by the restoring spring 135.

When the parts are in the position shown in Figure 13 in full lines the stove is in the idle or non-burning position and all the latches are lifted off the snuffer supporting rods. When the handle 5 is shifted from the full line position to the dot-and-dash line position of Figure 13, the plate 133 is swung to carry the lever 136, which bears on the upper end of shaft 123, to such a position that the end 137 of the lever enters an opening 138 10 in the fixed plate 138' which covers the blower chamber. A spring 139 acts on this lever to withdraw the lever when the motor stops and the weights automatically lower the shaft 123. The movement of the hand lever 134 has also shifted 15 the links 132 to stress the springs 133, so that the latches 130 are tensioned to enter under the shoulders of the snuffer rods when the snuffer rods are lifted. This lifting operation is effected by a control shaft 140 acting on an arm 141 which is 20 adapted to be brought into engagement with the lower end of the snuffer rod. In this construction the oil supply lines may be provided as indicated at 142.

In the arrangement shown in Figure 17 the 25 single burner unit oil stove is supported in any convenient manner, as, for example, by legs indicated at 150. The motor 151, motor housing 152, fan 153 and speed responsive mechanism 154 may be substantially the same as that previously described in detail. They are mounted 30 on a vertical axis and the air is blown out through openings 155 in the side wall of the blower housing 156. The air is blown out into an air-chest 157 and passes upwardly through 35 the inside of a burner tube 158 and through an outer air collar 159, these parts being secured together by bridging members 160. The burner tube 158 carries the usual wick, the air distributor 161 and flame spreader 162. The snuffer 40 163 is carried on a rod 164, and is adapted to be held in normal operating position by a lever 165 pivoted at 166 and acted on by the speed responsive mechanism 154. The parts are shown in Figure 17 in the burning position, and in 45 this position the snuffer 163 is held elevated. Should the motor stop the lever 165 will shift to the dot-and-dash line position releasing the snuffer, and the snuffer will drop to extinguish the flame. The snuffer lifter arm is indicated 50 at 167. It is pivoted at 168 and is adapted to be actuated by a button 169. For convenience the wick adjuster and oil supply pipes are omitted from Figure 17.

Figure 18 shows a heater 170 using two of the 55 burners, such as shown in Figures 1-8, except that the fire collar is omitted as there is no need of confining the flame to a small area.

It is obvious that the invention may be embodied in many forms and constructions within 60 the scope of the claims and we wish it to be understood that the particular forms shown are but a few of the many forms. Various modifications and changes being possible, we do not otherwise limit ourselves in any way with respect 65 thereto.

What is claimed is:

1. A burner for use in oil stoves comprising a double walled wick tube, a wick, an air distributor within the wick tube, a flame spreader 70 extending over and spaced from the wick, an air-chest communicating with the inside of the wick tube, an outer air tube communicating with the air-chest, spaced from the outside of the wick tube and carrying a constricted collar terminating close to the upper end of the wick tube,

means for blowing air into the air-chest to create a forced draft through the passages defined by the air distributor, the flame spreader, the wick tube, the outer tube and the collar to cool the lower part of the wick tube and provide air to maintain combustion at the top of the wick, a vertically reciprocable rod extending up through the wick tube and flame spreader, a snuffer carried by the upper end of the rod above the flame spreader and having a diameter greater than 10 the wick, releasable rod holding means for supporting the rod in an elevated position with the snuffer above the wick where it does not interfere with flame propagation, the rod, when released, dropping to bring the snuffer down to 15 cover the top of the wick to cut off the flow of the air supply from the top of the wick and extinguish the flame.

2. A burner as claimed in claim 1, wherein the flame spreader has holes under the snuffer to 20 pass air for cooling the snuffer, this air flowing out under the periphery of the snuffer to further spread the flame.

3. A burner as claimed in claim 1, wherein the wick tube and outer air tube are supported from 25 the top wall of the air-chest, the wall having apertures therebetween to pass air into the chamber formed by the wick tube and air tube.

4. A burner as claimed in claim 1, wherein the snuffer is imperforate to protect the wick against 30 fouling by foreign matter dropped from above.

5. A burner as claimed in claim 1, wherein the snuffer rod extends down through an axially disposed, fixed guide tube.

6. A burner as claimed in claim 1, wherein the 35 snuffer rod extends down through an axially disposed, fixed guide tube, and the holding means for the rod is in the form of a spring pressed latch co-operable with a shoulder on the rod.

7. A burner as claimed in claim 1, wherein the 40 snuffer and flame spreader and air distributor are upwardly removable.

8. A burner as claimed in claim 1, wherein the constricted collar is upwardly removable past the snuffer.

9. A burner as claimed in claim 1 having a 45 fire collar outside the constricted collar terminating adjacent the top of the wick to limit the spread of the flame.

10. A burner as claimed in claim 1 having a 50 fire collar outside the constricted collar terminating adjacent the top of the wick to limit the spread of the flame, the constricted collar being perforated to pass air into the fire collar.

11. A burner as claimed in claim 1 having a 55 fire collar outside the constricted collar provided with a lower divergent portion and an upper convergent portion extending above the snuffer, the fire collar receiving air through holes in the constricted collar and diverting the flame upwardly 60 and inwardly over the snuffer.

12. A burner as claimed in claim 1, wherein the flame spreader is movable independently of the air distributor and having manually operable means for lifting the snuffer and the flame 65 spreader above the normal or burning position, so as to provide additional space for the escape of air and for the insertion of a match.

13. A burner as claimed in claim 1, wherein the flame spreader is movable independently of the 70 air distributor and having manually operable means for lifting the snuffer and the flame spreader above the normal or burning position, so as to provide additional space for the insertion of a match, and means controlled from said snuff- 75

er lifting means for providing a vent in the air-chest to reduce the air being blown past the top of the wick.

14. A burner for use in oil stoves comprising a wick, a wick tube, an interiorly disposed air distributor, a flame spreader extending over and spaced from the wick, a superposed vertically reciprocable snuffer which in the lower position fits about the wick tube to prevent flame propagation, means acting from below the air distributor to lift the snuffer to space it from the wick so that air may pass by the wick to propagate a flame, and means below the air distributor for keeping the snuffer in said lifted position.

15. A burner such as claimed in claim 14, having manually operable means to lift the snuffer to a still higher elevation to facilitate applying a match to the wick.

16. A burner such as claimed in claim 14, having manually operable means to lift the snuffer to a still higher elevation to facilitate applying a match to the wick, said manually operable means also lifting the flame spreader to space it farther away from the wick.

17. A burner such as claimed in claim 14, wherein the snuffer holding means includes a releasable latch, and the snuffer is disconnectably connected thereto so as to be upwardly removable.

18. A burner for use in an oil stove comprising a wick, a wick tube, an interiorly disposed air distributor in the upper part of the wick tube, a flame spreader, an axially disposed guide tube below the air distributor, a rod slidably carried in the guide tube, and extending up through the flame spreader and the air distributor, and an inverted cup-shaped member secured to the rod to move up and down therewith and adapted, when the rod is in its lower position, to extend down about the upper edge of the wick tube.

19. A burner for use in an oil stove comprising a wick, a wick tube, an interiorly disposed air distributor in the upper part of the wick tube, a flame spreader extending over and spaced from the wick, an axially disposed guide tube below the air distributor, a rod slidably carried in the guide tube, and extending up through the flame spreader and the air distributor, an inverted cup-shaped member secured to the rod to move up and down therewith and adapted, when the rod is in its lower position, to extend down about the upper edge of the wick tube, the lower end of the rod extending below the guide tube and having a shoulder, and a releasable latch engageable with the shoulder to hold the rod in an elevated position.

20. A burner such as claimed in claim 19, having a rod lifter engageable with the rod to raise it up to the latching position.

21. A burner for use in an oil stove comprising a wick, a wick tube, an air distributor, a flame spreader extending over and spaced from the wick, a reciprocable snuffer having three positions, a lower or flame snuffing position adjacent the wick, an intermediate or burning position spaced from the wick and an elevated position for lighting, releasable means for holding it in the intermediate position, and manual means for raising it from the lower position to the intermediate position or from the intermediate position to the upper position.

22. In an oil stove, a wick type burner, means for producing forced draft from below the burner to provide air for combustion, a vertically reciprocable snuffer above the wick, means to hold the snuffer spaced from the wick to permit air to

pass to propagate a flame, means to support an article to be heated above the snuffer and close to it when the snuffer is in position for burner operation so that the heat is applied directly thereto, and means to disable the snuffer holding means whereupon the snuffer drops to cut off the air supply from the wick.

23. An oil stove comprising a burner of the wick type, a superposed, vertically reciprocable snuffer which in the lower position fits about the wick tube of the burner to prevent flame propagation, a blower, a conduit from the blower to the burner, means to lift the snuffer to space it from the wick so that air may pass by the wick to propagate a flame, means to keep the snuffer in the lifted position, and means responsive to cessation of blower operation to release the snuffer holding means so that the snuffer drops to extinguish the flame.

24. An oil stove comprising a burner of the wick type, a superposed, vertically reciprocable snuffer which in the lower position fits about the wick tube of the burner to prevent flame propagation, a blower, a conduit from the blower to the burner, manually operated means to lift the snuffer to space it from the wick so that air may pass by the wick to propagate a flame, latch means to keep the snuffer in the lifted position, and means responsive to cessation of blower operation to release the snuffer latch so that the snuffer drops to extinguish the flame.

25. An oil stove comprising a burner of the wick type, a superposed, vertically reciprocable snuffer which in the lower position fits about the wick tube of the burner to prevent flame propagation, a blower, a conduit from the blower to the burner, a screen interposed between the blower and burner to diffuse the air, means to lift the snuffer to space it from the wick so that air may pass by the wick to propagate a flame, means to keep the snuffer in the lifted position, and means responsive to cessation of blower operation to release the snuffer holding means so that the snuffer drops to extinguish the flame.

26. A forced draft oil stove comprising a wick type burner, a motor operated blower connected to the burner through a conduit to conduct air to the burner, a snuffer disposed above the burner and normally covering the wick, manual means for lifting the snuffer to space it from the wick so that air may pass by the wick to propagate a flame, a snuffer retaining latch, a latch lifter, and motor operated means for rendering the latch lifter non-functioning while the motor is in operation, the last-mentioned means acting on stoppage of the motor to release the latch so that the snuffer drops to extinguish the flame.

27. A forced draft oil stove comprising a wick type burner, a motor operated blower connected to the burner through a conduit to conduct air to the burner, a snuffer disposed above the burner and normally covering the wick, manual means for lifting the snuffer to space it from the wick so that air may pass by the wick to propagate a flame, a snuffer retaining latch, a spring urging the latch to latching position, a spring controlled member normally overcoming the latch spring to release the latch, and a responsive device acting on the spring controlled member when the motor is operating the blower to shift said member to latching position and hold it there while the motor is operating.

28. An oil stove having a front wall, a back wall, an apertured top, grates in the apertures, a burner under each grate, each burner having

a wick tube, air distributor and flame spreader, wick adjusters accessible at the front of the stove, a blower, an air-chest connected to the blower and extending past the burners, air passages from the air-chest for forcing air up past the wick both inside and outside the wick, and snuffing means

between each grate and the corresponding burner for extinguishing the flame upon cessation of blower operation.
